UNITED STATES PATENT OFFICE.

HAROLD I. STAGE, OF EASTON, PENNSYLVANIA.

PNEUMATIC DRILL COLUMN.

1,418,336.

Specification of Letters Patent. Patented June 6, 1922.

Application filed January 13, 1919, Serial No. 270,877. Renewed April 18, 1922. Serial No. 555,236.

To all whom it may concern:

Be it known that I, HAROLD I. STAGE, a citizen of the United States, residing at Easton, in the county of Northampton and State of Pennsylvania, have invented a certain new and useful Improvement in Pneumatic Drill Columns, of which the following is a specification.

This invention relates to a pneumatic column or support upon which a rock drill may be mounted and thus supported in operative position.

The objects of the present invention are to provide a supporting column for rock drills having pneumatic means for holding it in place and also a resiliently mounted member forming a foot piece at one end to engage the sides of the drift, this latter mentioned member being for the purpose of retaining the column in position should the pressure on the line drop or fail. A further object of the invention is to provide a pawl engaged extension member which may be extended by the pneumatic means to engage one of the faces of the drift opposite that engaged by said foot piece and which is prevented by means of this pawl from disengaging the drift after being placed in position. Furthermore, it is an object of the present invention to provide a pneumatic column for rock drills which may be readily set up in position in the rock being operated upon and quickly taken down and removed again. Also, to provide a column which will be simple, durable, and rigidly held in place when in use.

With these and other objects in view my invention consists in the features of construction and operation set forth in the following specification and illustrated in the accompanying drawings, forming a part hereof, in which,

Figure 1 is a view of the assembled column, parts being shown in section;

Figure 2, a slightly modified form of the extension member;

Figure 3, a cross sectional view of the throttle valve;

Figure 4, a further section through the throttle valve; and

Figure 5, the resiliently mounted member forming a foot piece, provided with prongs for engagement with a side of the rock.

Briefly, the column comprises a cylindrical member or cylinder casing 1 of sufficient length to accommodate an extension member or piston rod 2 encased within it, a throttle

valve 3 near one end of the cylindrical member 1 mounted within a column head 13, the column being further provided with a resiliently mounted prong supporting member 6 adapted to engage one face of the rock in which the column is being used. The resilient mounted member 6 serves as a support for a rock engaging member or foot piece 23, preferably of double prong construction, as shown, and adapted to engage the face of the rock at a plurality of points opposite that engaged by the foot piece 11 (preferably of single prong construction as shown) 70 provided on said extension member 2.

The assembly of the resilient supporting member 6 and prong member 23 is shown clearly in Figure 5. The inner end 24 of the resilient supporting member 6 is reduced 75 in diameter to provide a chamber between the column head 13 and the resiliently mounted member 6 in which a heavy spring 25 is adapted to set. Spring 25 is of such length and size of wire that a force almost 80 equal to the total pressure exerted within the cylinder member 1 is required to compress it to its position shown in Figure 1. At the outward end of the resiliently mounted supporting member 6 is the bolt 26 85 about which the prong member 23 is transversely pivoted. For convenience in holding the member 6 and bolt 26 together the bolt 26 rests in depressions 27 provided on either side of the member 6.

The extension member 2 at its inner end is made in the form of a piston 4 provided with suitable piston packing 5 which is usually in the form of cup leathers, to make a tight joint between the walls of the cylindrical member 1 and the piston 4. Along the sides of this extension member is a series of teeth 7 forming a rack into which engages a pawl member 8 mounted upon the end of the cylindrical member 1. This rack and 100 pawl forms a non-return stop between the piston rod and the cylinder casing. Preferably this pawl member 8 is held into engaging position with the rack by means of a spring pressed plunger 9 forcing an extension on the handle member 10 of the pawl outwardly. The outer end of the extension member 2 is provided with a pointed extremity 11 forming a pointer or rock engaging member adapted to engage into one of 110 the surfaces of the rock and also on the end of this member is provided a flange or shoe 12 surrounding this prong, which may be used to engage the rock when the column is

used in very soft material such as coal or clay. At the opposite end of the column the resiliently mounted member 6 is provided mounted upon the column head 13 which is 5 attached to this cylindrical member 1. The inner end of this resiliently mounted member 6 is surrounded by an extension spring tending always to force it outwardly from the column. To prevent the resilient member 6, however, from disengaging the column completely, a bolt 26 is provided engaging the sides of this resilient member 6 and engaging slots 14 in an extension plate 15 provided on the column head 13 rotatably 10 engaging the bolt 26 above referred to and 15 also the resilient member adapted to engage the face of the drift.

The column head 13 is preferably located in the lower portion of the cylindrical member when the column is used in its upright position and is provided with a throttle valve 3 as above stated, receiving from a suitable source of supply, motive fluid, which is usually in the form of compressed air. The 25 throttle valve 3 which has the usual handle 3^a and stop pin 3^b is provided with a pressure receiving recess 16 supplied with motive fluid from a suitable source and a radial slot 17 adapted upon rotation of the throttle to intercept a passage 18 leading to the cylinder member below the piston 4 provided on the extension member 2. Another radial passage 19 of larger cross section than the one above described is provided leading to an outlet 20 30 from another part of the throttle valve casing adapted to supply fluid to a rock drill which may be mounted upon the column. A bleeder port 21 is also provided so that when the throttle is returned to neutral or closed position (180° from that shown) the pressure within the cylinder member may be exhausted through the bleeder port 21 and passages 22. The stop pin 3^b is located in such a position that the throttle valve cannot be rotated 35 backwardly far enough to permit port 17 to communicate with passage 20, and thus supply fluid pressure to the rock drill before introducing pressure into the column. In the position of throttle valve 3 shown in Figures 40 3 and 4 the port 17 is open admitting motive fluid to the cylinder 1, thus holding the column in position and the port 19 is open admitting motive fluid to operate a drill mounted on the column. Rotation of the throttle 45 valve 3 in the direction shown by the arrow first closes outlet 20, then closes passage 18 to fluid pressure supply, and finally opens the passage 18 to the bleeder port 21 thus releasing pressure from cylinder 1 and allowing the column to be taken apart. Stop pin 3^b prevents further rotation of the throttle 50 55 valve in this direction.

In operation, the column 1 may be utilized somewhat as follows: The column 1 is first set up in approximately the position desired,

either vertically or horizontally, and the connection with the fluid pressure supply is made; the throttle valve 3 is then rotated to supply fluid pressure to the cylindrical member below the extension member 2, which 70 forces the piston 4 and extension member 2 outwardly and forces the prong 11 and shoe 12 against the surface of the drift opposite to that of the double prong member 23 shown at the bottom of Figure 1. The pawl member 75 8 engages one of the teeth 7 in the rack provided in the extension member 2, thus preventing the return of extension member 2 should the pressure within the cylinder fail. The pressure within the cylinder also has the 80 effect of forcing the cylindrical member 1 against the resiliently mounted member shown at 6 at the bottom of Figure 1, this movement being sufficient to force the extension member 2 outwardly one or more additional teeth against the pressure of the spring. With the column thus rigidly in place and with pneumatic pressure within the cylindrical member and the pawl engaging the last tooth possible, a failure of the pressure on the line will merely allow the spring 25 which has been compressed as above described to expand, forcing the resiliently mounted member 6 and double prong member 23 outwardly sufficiently to retain the column in 95 place. For simplicity and economy of flexible piping the supply of motive fluid to the rock drill or other tool mounted upon the column is taken directly from the throttle valve and column. This arrangement has the 100 further advantage that the drill cannot be operated until the column is set up in place and rigidly held in place.

In Figure 2 a modified form of extension member is shown in which the pointed extremity 11 and shoe 12 are resiliently mounted within the extension member 28. This is conveniently accomplished by providing a spring 29 below the pointed member 11. When the column is in use the spring 29 is 110 compressed in a manner and for a purpose similar to that described for spring 25. In this modified form of the invention spring 25 is omitted and the foot piece made without a resilient mounting. This may be easily accomplished by pivotally mounting the double pronged member 23 directly to the member 15. To limit the movement of the resiliently mounted member 11 within the extension member 28 slots 33 are provided through 115 which a bolt 34 is passed engaging the member 11 thus holding these two parts resiliently together. This form of the invention is also provided with the cup leathers inserted in piston 31 and held in position thereon by 120 means of the cap screw 32.

It is to be understood that the present showing and description disclose only certain specific embodiments of the present invention, and that other forms and modifications 130

are included within the spirit and scope of the invention, as expressed in the appended claims.

What I claim is:

- 5 1. A column adapted to support a fluid actuated percussive tool in operative position comprising a transversely pivoted adjustable rock engaging foot capable of accommodating itself to inequalities of the 10 floor, a cylinder casing non-rotatively connected to the said pivoted foot, a fluid actuated piston in the cylinder casing, a piston rod connected to said piston, said piston rod extending beyond the end of the cylinder 15 casing, a rack and pawl engagement between said piston rod and cylinder casing, a rock engaging pointer at the end of the piston rod, and means for exerting spring pressure tending to force one of the rock engaging 20 members outward beyond the position assumed due to the fluid actuating pressure in said cylinder, whereby upon failure of fluid pressure the said pawl engages the rack on the piston rod and in conjunction with said 25 spring causes the rock engaging members to continue to exert pressure against the rock.
2. A column adapted to support a fluid actuated percussive tool in operative position, comprising a lower rock engaging member, engaging the rock at a plurality of points, a cylinder casing non-rotatively connected to said lower member, a fluid actuated piston in the cylinder casing, a piston 35 rod connected to said piston and extending beyond the end of the cylinder casing, a rack and pawl engagement between said piston rod and cylinder casing, an upper rock engaging member at the outer end of the 40 piston rod and a spring normally compressed by the force of the fluid pressure in the cylinder and tending to separate the two rock engaging members, so that when the 45 pressure exerted by the fluid falls below the pressure exerted by the spring, the spring maintains the upper rock engaging member in contact with the rock, and the pawl prevents the piston from retracting in the cylinder casing.
- 50 3. A column adapted to support a fluid actuated percussive tool in operative position, comprising a lower rock engaging member engaging the rock at a plurality of points, a cylinder casing connected to said lower member, a fluid actuated piston slide- 55 able in said cylinder casing, a piston rod connected thereto and extending beyond the end of the cylinder casing, a rack and pawl engagement between said piston rod and cylinder casing, an upper rock engaging member at the outer end of the said piston rod, and a spring normally compressed by the force of the fluid pressure in the cylinder and thereby tending to force the two rock 60 engaging members apart, so that when the 65 pressure exerted by the fluid falls below the pressure exerted by the spring, the spring maintains the upper rock engaging member in contact with the rock, and the pawl prevents the piston from retracting in the cylinder casing, the weight of the cylinder casing and a drill mounted thereon being taken at all times by the cylinder casing and lower rock engaging member or foot. 75
4. A column adapted to support a fluid actuated percussive tool in operative position, comprising a lower rock engaging member, engaging the rock at a plurality of points, a cylinder casing non-rotatively connected to said lower member, a fluid actuated piston in the cylinder casing, a piston rod connected to said piston and extending beyond the end of the cylinder casing, an upper rock engaging member at the outer end of the piston rod and a spring normally compressed by the force of the fluid pressure in the cylinder and tending to separate the two rock engaging members, so that when the pressure exerted by the fluid falls below the pressure exerted by the spring, the spring maintains the upper rock engaging member in contact with the rock, and the pawl prevents the piston from retracting in the cylinder casing, a throttle valve mounted on the column for controlling the supply of motive fluid to the column and to a tool adapted to be mounted on the column, the partial turning of said valve opening communication between a source of supply and the column, and further turning of said valve opening communication between the source of supply and the percussive tool while maintaining the supply to the column. 95
5. A column adapted to support a fluid actuated percussive tool in operative position, comprising a rock engaging member at one end, adapted to engage at a plurality of points, a cylinder casing non-rotatably connected to the said rock engaging member, a fluid actuated piston in the cylinder casing, a piston rod connected to said piston and extending beyond the end of the cylinder casing, a non-return stop between the piston rod and cylinder casing, a rock engaging member at the end of the piston rod, and means for exerting spring pressure tending to force one of the rock engaging members outward beyond the position assumed due to the fluid actuating pressure in said cylinder, whereby upon failure of fluid pressure the said non-return stop prevents the return of the piston rod into the cylinder casing and in conjunction with said spring causes the rock engaging members to continue to exert pressure to maintain the column in position. 105
